UNITED STATES PATENT OFFICE.

LEWIS W. HEWETT, OF NEW YORK, N. Y., AND THOMAS MILLEN, OF JERSEY CITY, NEW JERSEY, ASSIGNEES TO PHILIP B. SHAW, OF WILLIAMSPORT, PENNSYLVANIA.

CAR-STARTER.

SPECIFICATION forming part of Letters Patent No. 280,744, dated July 3, 1883.

Application filed February 21, 1883. (No model.)

To all whom it may concern:

Be it known that we, LEWIS W. HEWETT, of the city, county, and State of New York, and THOMAS MILLEN, of Jersey City, in the 5 county of Hudson and State of New Jersey, have invented a certain new and useful Improvement in Car-Starters, of which the following is a specification.

Our invention relates to that class of car-starters in which a sleeve surrounds the axle, and a collar is placed around said sleeve, and intermediate gripping devices are provided between said sleeve and said collar, a lever being attached to the collar and connected 15 with the draw-bar, so that the pulling of the horses turns the collar on the sleeve, and causes said gripping devices to clamp the sleeve and turn the axle in a forward direction. Two of these starters are used, one on each axle of the 20 car, so that one is used as the car moves in one direction and the other when its direction is reversed; but if the car is always drawn from one end, only one car-starter is used. In such a car-starter means are provided whereby, 25 when it is not in use, the gripping devices may be removed from operative position, so that they will not act to prevent the movement of the car in the other direction. The arrangements of this kind heretofore in use 30 have been comparatively unsuccessful, because, although when the car started, the gripping devices would be raised out of operation, yet as the load within the car increased the settling of the body of the car on the springs 35 would cause them to drop back and clamp the axle. Another difficulty has been that the driver would, in detaching his horses from the car, forget to raise the gripping devices from position, and the car would be locked by the 40 starter against movement in the other direction.

Our principal object is to obviate these objections, which we accomplish by providing means for locking the gripping devices out of 45 operative position independent of the vertical movement of the car-body, such means being thrown into operation by the same movement which throws them out of such position, and

separate means being provided for releasing them when it is desired to use them again, 50 and by providing means which shall prevent the unhitching of the horses from the draw-bar until the starter is thrown out of action, such means consisting of a movable bolt normally covering the draw-bar hook, but drawn 55 back by the same movement which throws the starter out, so that the hook is uncovered. In addition, our object is generally to improve the efficiency of car-starters of the kind described.

The particular construction of car-starter to 60 which we prefer to apply our improvements is that set forth in the joint application of the said Hewett and Sumner J. Leonard, (Serial No. 60,187.)

Our invention may be carried into effect by 65 means illustrated in the annexed drawings, in which—

Figure 1 is a view in elevation of a car-starter and the devices for operating it, and Fig. 2 a view of the bolt which covers the 70 draw-bar hook and the means by which it is withdrawn.

A represents one of the wheels of a car, and B the axle thereof. Upon said axle is fixed a sleeve having an enlarged central portion, C. 75 The sleeve turns within a collar, D, which surrounds the enlarged portion C. A portion of said collar is formed into a chamber, c. A groove or grooves are provided in the portion C, within which work the gripping devices intermediate between the sleeve and collar, which may be one or more balls or rollers. Preferably several rollers, a, (one of which is shown in dotted lines,) each working in a separate groove, are used, as in the application referred to. 80

A rigid lever, E, is attached to collar D, from which lever extends a chain, F, passing over a sheave attached to the bottom of the car at G, and being attached to the draw-bar 90 H, which is provided with a spring inclosed by the box b, and which terminates in a hook, I, at the end of the car, to which hook the horses are to be attached.

When the mechanism is in operative position, the gripping devices a are in contact with

the sleeve C. The pulling of the horses on the draw-bar turns the collar D upon the sleeve C, and causes the devices *a* to grip said sleeve and assist in turning the axle, and when the car stops and the traces slacken the collar D falls back and is ready for operation when the car starts again.

A spring, J, may be provided to assist in bringing the collar back into position, it being desired to do this very quickly.

To throw the gripping device or devices *a* out of position we employ a rod, *d*, for each of them, such rods passing through the bottom of chamber *c*, and being guided by 15 through holes in a wing, *e*. The rods *d* are moved by arms *f*, *g*, and *h*, the rod *h* being attached to a rock-shaft, *i*, mounted on the collar D. An arm, *j*, from the rock-shaft *i* extends to pin *k*, and from pin *k* the rod K, having a slot, *k'*, runs to the end of the car, where it is attached to arm *l* of rock-shaft *m*. The arm *n* of said rock-shaft is attached to the lower end of the step L. Thus the pressing down of the step L causes the movement of the rod K, and through the intermediate arms the gripping devices *a* are thrown up out of contact with the sleeve C. A weighted arm, *m'*, attached to shaft *m*, turns said shaft to throw the step up again, the slot *k'* allowing this to be done without interference with the throwing out and locking devices. If no means are provided for holding the gripping device *a* out of position, the settling of the car on its 20 axis may allow such devices to fall back and again grip the sleeve. We therefore provide a locking device which consists of the arm *o*, attached to arm *j* and provided with a catch, *p*, which, when the arms *j* and *o* are pushed forward by the throwing back of the rod K, 25 engages with a projection, *q*, on the collar D, and thus holds the arm *j* back and keeps the rods *d* pressed up and holding the gripping devices *a*. This locking-arm *o* being pivoted to a part mounted upon the collar of the starter, and also locking with a projection from such collar, the gripping devices will be held by it out of operative position independent of the vertical movement of the car on its springs.

To release the catch *p*, a rod, L', terminating 30 in a ring-handle, is placed in a convenient position at the end of the car, and is connected with arms *r* *s* of a bell-crank sleeved on the rock-shaft *m*.

From arm *s* runs a rod, M, attached at its 35 other end to the arms *t* *u* of a bell-crank. When rod L is pulled up, arm *t* strikes the end of rod *o* and raises the catch *p*, thus allowing the gripping devices to fall again into operative position. A spring, *v*, is attached 40 to rod M, to return it and the parts attached to it to their former positions.

Passing through the step L is a bolt, N,

having a pin, *w*, which enters a curved slot, *x*, in the step. The bolt normally covers the draw-bar hook I, as shown, so that the horses 45 cannot be detached from the car until the step is pressed down, when the pin in the slot causes the drawing back of the bolt and uncovers the hook. When the direction of the car is to be reversed, the driver pushes down the step I, and thus throws out the gripping devices and locks them. He is then able to unhook the horses from the draw-bar. Before starting, he raises the rod L' at the then forward end of the car, and thus throws the 50 starter at that end into action.

What we claim is—

1. In a car-starter, the combination, with gripping devices intermediate between the axle, and a loose collar mounted thereon, of 55 means for throwing such gripping devices out of action, and means attached to said collar for locking them out of action, substantially as set forth.
2. In a car-starter, the combination, with 60 the movable intermediate gripping devices, of the rock-shaft for operating throwing-out devices for said gripping devices, mounted directly upon the loose collar, and a catch operated also by said rock-shaft and engaging with a projection on the collar, whereby said gripping devices are locked when thrown out, substantially as set forth.
3. In a car-starter, the combination, with 65 the loose collar and the gripping devices, of means attached to said collar for locking such devices out of action, and means operated from the platform of the car for releasing them, substantially as set forth.
4. In a car-starter, the combination, with 70 the catch engaging with a projection on the collar to lock the gripping devices, of a device for raising said catch from said projection, operated from the end of the car, substantially as set forth.
5. In a car-starter, a device covering the 75 end of the draw-bar hook, in combination with means for withdrawing such device, such means being actuated by the same movement which throws out the gripping devices, substantially as set forth.
6. In a car-starter, the combination of the 80 bolt covering the end of the draw-bar hook, the step whose downward movement throws out the gripping devices, and means whereby such movement also withdraws the bolt, substantially as set forth.

This specification signed and witnessed this 1st day of February, 1883.

LEWIS W. HEWETT.
THOMAS MILLEN.
